(57) **CLAIM**

The ornamental design for a loader component as shown and described.

DESCRIPTION

FIG. 1 is a front view of a first embodiment of a loader component;

FIG. 2 is a rear view of the first embodiment of the loader component;

FIG. 3 is a left view of the first embodiment of the loader component;

FIG. 4 is a right view of the first embodiment of the loader component;

FIG. 5 is a top view of the first embodiment of the loader component;

FIG. 6 is a bottom view of the first embodiment of the loader component;

FIG. 7 is a first perspective view of the first embodiment of the loader component;

FIG. 8 is a second perspective view of the first embodiment of the loader component;

FIG. 9 is a front view of a second embodiment of a loader component;

FIG. 10 is a rear view of the second embodiment of the loader component;

FIG. 11 is a left view of the second embodiment of the loader component;

FIG. 12 is a right view of the second embodiment of the loader component;

FIG. 13 is a top view of the second embodiment of the loader component;

FIG. 14 is a bottom view of the second embodiment of the loader component;

FIG. 15 is a first perspective view of the second embodiment of the loader component; and,

FIG. 16 is a second perspective view of the second embodiment of the loader component.

(Continued)

The relatively de-emphasized and light broken lines depict portions of the loader component that form no part of the claimed design.

1 Claim, 16 Drawing Sheets
